UNITED STATES PATENT OFFICE.

LUCILE BYLAND, OF PORTLAND, OREGON.

EGG AND CREAM BEATER.

Application filed June 14, 1928. Serial No. 285,448.

The present invention relates to improvements in agitating devices, and has reference more particularly to an egg and cream beater.

5 One of the important objects of the present invention is to provide a beater of the above mentioned character which is of such construction as to permit the stirrers and the supporting rods therefor to be readily and 10 easily cleaned, thus promoting sanitation.

A further object is to provide a beater of the above mentioned character which is simple in construction, inexpensive, strong and durable, and further well adapted to the 15 purpose for which it is designed.

Other objects of the invention will become apparent as the nature of the invention proceeds and when taken in connection with the accompanying drawings.

20 In the accompanying drawings, forming a part of this application and wherein like reference characters designate like parts throughout the several views:

Figure 1 is a side elevation of the beater 25 embodying my invention.

Figure 2 is a view, looking at right angles to Figure 1, the stirrers not being illustrated.

30 Figure 3 is a transverse section taken approximately on the line 3—3 of Figure 1, looking downwardly.

Figure 4 is a detail perspective view of the frame of the beater, and

35 Figure 5 is a detail perspective view of the U-shaped member that is secured in the frame to maintain the pinion carried by the upper end of the spindle or stirrer rod in engagement with the driving wheel.

In the drawings, wherein for the purpose 40 of illustration is shown the preferred embodiment of my invention, the numeral 1 designates generally my improved beater, the same comprising the frame 2, which is constructed from a single strip of metal, so 45 bent as to form an elliptical shaped body 3, the elongated sides of which are disposed in parallel spaced relation with respect to each other. This elliptical shaped body is formed at the intermediate portion of the 50 elongated flat strip from which the frame 2 is constructed, and parallel spaced arms 4 and 5 extend upwardly from the open portion of the top side of the elliptical shaped body and the upper ends of these arms are 55 disposed in abutting relation to provide a

handle attaching portion 6, the handle being shown at 7.

A crank shaft 8 has one end extending through registering openings formed in the intermediate portions of the parallel spaced arms 4 and 5, for supporting between said arms, the driving wheel 9 which is adapted for rotation between said arms and a portion of this driving wheel extends into the elliptical shaped body 3, as clearly indicated 60 in the drawings. A suitable handle 10 is arranged on the outer end of the crank shaft 8 for facilitating the manual cutting thereof.

The driving wheel 9 has the radial teeth 11 projecting alternately from opposite surfaces at the perimeter of said driving wheel 70 in the manner well known in the art.

A substantially U-shaped bracket 12 is arranged at one side of the intermediate portion of the elliptical shaped body 3 and 75 formed on the upper ends of the arms are the horizontally disposed outwardly projecting plates 13 and 14 that are disposed within the elliptical shaped body and are secured at their ends to the rounded ends 80 of the body in any appropriate manner. These laterally disposed plates are formed with suitable openings, through which are disposed the upper ends of the stirrer rods 15 and 16 respectively, the top and bottom 85 sides of the elliptical shaped body being formed with openings to accommodate the upper ends of these rods or spindles.

A substantially circular ring like stirrer 17 is associated with the lower end of each 90 stirrer rod and as is shown in Figure 1, each stirrer comprises a flat piece of metal bent into ring formation, the ends of the split ring being disposed laterally as at 18 and soldered or otherwise permanently secured to the lower enlarged end 19 of each stirrer rod.

The stirrers are adapted for cooperation 100 with each other in the manner well known in the art. A pinion carrying hub 20 is fixedly secured on the upper portion of the stirrer rod 14 for disposition within the lower portion of the elliptical shaped body 3, the pinion associated with this hub being 105 designated by the numeral 21. This pinion engages with the teeth that project from one side of the driving wheel 9. A similar pinion 22 is carried by the hub 23 that is secured in a stationary manner on the upper portion of the other stirrer rod 16 and the 110

pinion 22 has cooperation with the teeth that project from the other side of the driving wheel in the manner as clearly indicated in Figure 3.

5 The laterally disposed plates 13 and 14 carried by the upper free ends of the arms of the U-shaped member 12 engage with the upper ends of the respective hubs to prevent vertical movement of the hubs and the 10 spindles or stirrer rods, so that the pinions will, at all times, have cooperative relation with the teeth of the driving wheel 9.

The operation of the beater is thought to be readily obvious from the construction 15 shown and as this operation is well known in the art, a further detailed description of the same is believed unnecessary in the present instance.

It will thus be seen from the foregoing 20 description that I have provided a beater construction that will eliminate the use of the usual U-shaped wire for supporting the stirrer members and will thereby promote sanitation and permit the stirrers and their 25 supporting rods to be readily and easily cleaned. Furthermore, a beater of the above mentioned character can be constructed at a very low cost, and the same will, at all times, be positive and efficient in 30 its operation.

While I have shown the preferred embodiment of my invention, it is to be under-

stood that various changes in the size, shape and arrangement of parts may be resorted to, without departing from the spirit of the 35 invention or the scope of the appended claim.

I claim:

In a beater, a frame, a handle supported at the top of the frame, a pair of stirrer rods journaled at their upper ends in the lower portion of the frame, horizontally disposed pinions secured on the upper ends of the stirrer rods for disposition within the frame, stirrers on the lower ends of the 40 rods, a vertically disposed driving wheel arranged in the frame for cooperation with the pinion, means for actuating the driving wheel, substantially U-shaped brackets arranged within the lower portion of the 45 frame, the arms of the brackets being disposed on opposite sides of the drive wheel, horizontally disposed plates projecting outwardly from the upper ends of the arms of the U-shaped bracket and secured at their 50 ends to the adjacent portions of the frame, said plates being formed with openings to accommodate the upper ends of the stirrer rods, the bottom faces of the plates engaging with the upper ends of the hubs of the 55 respective pinions retaining the pinions in engagement with the driving wheel.

In testimony whereof I affix my signature.
LUCILE BYLAND.
